US00D999341S

(12) **United States Design Patent** (10) **Patent No.:** **US D999,341 S**
(45) **Date of Patent:** **** Sep. 19, 2023**

(54) **SPRAY GUN**

(71) Applicant: **Graco Minnesota Inc.**, Minneapolis, MN (US)

(72) Inventors: **Mark C. Richter**, River Falls, WI (US); **Dawn P. Svenkeson-Koubal**, Wayzata, MN (US); **Amelia J. Stech**, St Paul, MN (US)

(73) Assignee: **Graco Minnesota Inc.**, Minneapolis, MN (US)

(**) Term: **15 Years**

(21) Appl. No.: **29/781,119**

(22) Filed: **Apr. 28, 2021**

(51) LOC (14) Cl. **23-01**

(52) U.S. Cl.

USPC **D23/226**

(58) **Field of Classification Search**

USPC D23/213, 214, 223, 224, 225, 226, 227, D23/228, 229, 230, 238, 239, 240, 241, D23/242, 249, 250, 255, 257; D8/2, D8/14.1, 29.1, 29.2, 30
CPC B05B 1/16; B05B 1/1618; B05B 1/18; B05B 1/185; B05B 15/62; B05B 15/652; F16K 31/60; E03C 1/0404

(57) **CLAIM**

The ornamental design for a spray gun, as shown and described.

DESCRIPTION

FIG. 1 is a first isometric view of a spray gun;

FIG. 2 is a second isometric view of the spray gun;

FIG. 3 is a right side view of the spray gun;

FIG. 4 is a left side view of the spray gun;

FIG. 5 is a front elevational view of the spray gun;

FIG. 6 is a rear elevational view of the spray gun;

FIG. 7 is a top plan view of the spray gun; and,

FIG. 8 is a bottom plan view of the spray gun.

The broken lines in the Figures represent portions of a spray gun and form no part of the claimed design.

1 Claim, 6 Drawing Sheets
